CHARLES T. MEYER, OF NEWARK, NEW JERSEY, ASSIGNEE TO EDWARD C. SAMPSON, OF NEW YORK CITY.

Design No. 4,409, dated October 11, 1870.

DESIGN FOR A FLOOR OIL-CLOTH PATTERN.

The Schedule referred to in these Letters Patent and making part of the same

To all whom it may concern:

Be it known that I, CHARLES T. MEYER, of Newark, county of Essex, State of New Jersey, have originated and designed a new pattern for Floor Oil-Cloths, Carpets, or other fabrics, of which the following is a full, clear, and exact description, reference being had to the accompanying drawings making part of this specification, and marked or designated as three hundred and thirty-seven, (337,) which fully represent said design, and are sufficient, without further aid, to enable any person skilled in the art to repeat it for practical use.

The colors employed for the different portions of this design may be varied to suit the convenience and taste of the manufacturer.

What I claim as my invention, and desire to secure by Letters Patent, is—

The design or pattern for floor oil-cloths, carpets, or other fabrics, shown and described.

CHAS. T. MEYER.
